[57] ABSTRACT

A timer having means to rotate a shaft on which there is a first geneva wheel that engages the geneva pinion for a limited part of each revolution. The pinion is in mesh with a second wheel and moves that second wheel in short intervals of motion spaced by relatively long intervals of no motion. If the wheels are the same diameter, the second wheel will rotate at the same instantaneous speed as the first wheel during the time the first wheel drives the pinion. The wheel and pinion may be arranged to provide an overall stepdown speed ratio of, for example, 10:1 between the first and second wheels but by arranging the second wheel to move at the same speed as the first wheel and by locating the electrical contact to be actuated by the second wheel, the timing of the actuation of the contact can be controlled much more accurately than by actuating the contact directly from the first wheel, provided it is acceptable to actuate the contacts during only certain limited intervals of time.

GENEVA DRIVE REPEAT CYCLE TIMER

FIELD OF THE INVENTION

This invention relates to a repeat cycle timer using electromechanical operating means to control the actuation of electrical contacts by way of a geneva drive arrangement that transforms the continuously applied power of rotation to intermittent rotation at a relatively high instantaneous speed.

BACKGROUND OF THE INVENTION

In electromechanical timers it is frequently desirable to control the opening and closing of electrical contacts at a precisely determined instant during each repeated cycle. If the cycle is very long, it is theoretically possible to use a slow speed motor and, if necessary, additional gear reduction to a cam that makes one revolution each cycle and to arrange cam followers around the periphery of the path of movement of the cam so that the followers will be actuated at a precise instant during the cycle. The difficulty of such an arrangement is that small imperfections in the surface of the cam and in the cam followers or the contacts, or small displacements of the angular locations of any cam follower can effect large change in the times at which the contacts controlled by that follower are actuated. As a result, it is impractical to try to provide precise timing of a succession of rapidly occurring events during one relatively long cycle of a continuously moving electromechanical timer.

BRIEF DESCRIPTION OF THE INVENTION

According to the present invention the precision of actuation of the contacts may be increased many fold by driving the cam by a counter drive so that it rotates a revolution in the same total time as if it were rotated continuously. The drive mechanism is similar to a counter drive with geneva wheels in the form of counter wheels interconnected by geneva pinions, but it is not necessary that the wheels have numerals on them as they would if they were actually used in a counter. For simplicity, these wheels will be referred to as "counter wheels." The first counter wheel also operates as a drive wheel and is connected to the shaft of a main power unit, such as a synchronous electric motor. A geneva pinion located on an adjacent parallel shaft is engaged by the counter wheel at selected times, normally once each revolution. Furthermore, the pinion is in rotating engagement with the wheel during only a limited part of a revolution of the wheel. Thus the pinion remains stationary while the wheel rotates through most of the revolution until the wheel suddenly engages the pinion and causes the latter to rotate relatively rapidly for a short time. By connecting the pinion to another counter wheel the rapid motion of the pinion may be transmitted to the second wheel to cause it to move rapidly while the pinion is rotating.

For example, the first counter wheel may engage the pinion for one-tenth of a revolution of the wheel, and the pinion may be constantly in mesh with the second counter wheel. If the latter has a step-up ratio equal to the stepdown ratio from the first counter wheel to the pinion, the second counter wheel will rotate with the same instantaneous speed as the first wheel, but for only one-tenth of a revolution each time the first counter wheel engages the pinion. By providing electrical contact actuators controlled by a cam connected to the second counter wheel, the electrical contacts may be caused to open or close or both during the periods of relatively rapid movement of the cam so that, in effect, given the 10:1 ratio set forth hereinabove, the precision of accuracy of opening and closing the electrical contact is increased by a factor of 10:1.

One of the objects of the present invention is to provide an improved repeat cycle timer in which the timing operations take place at very accurately predetermined times in the cycle. Further objects will become apparent from the following specification together with the drawings.

IDENTIFICATION OF THE DRAWINGS

FIG. 1 is a side view of a repeat cycle timer constructed according to the invention;

FIG. 2 is an exploded view from the side showing the components of a timer constructed according to the invention.

DESCRIPTION OF THE PREFERRED EMBODIMENTS

Referring now to the drawings, FIG. 1 illustrates a timer comprising a motor 10 mounted on a frame piece 11. The motor shaft 12 passes through an aperture 13 in the frame and has mounted thereon a counter wheel 14. A knurled portion 16 of the shaft serves to rigidly fix the wheel 14 so that the wheel will rotate at the same speed as the shaft. A second shaft 17 is mounted between second and third frame pieces, 18 and 19 respectively. This shaft is arranged to be able to rotate freely but is not directly connected to the first shaft 12, although it is aligned axially therewith. A knurled portion 21 serves to fix a second counter wheel 22 thereto in such a manner that when the wheel 22 rotates, the shaft 17 will also rotate. As can be seen in FIG. 1 the two counter wheels 14 and 22 are positioned with only a very small gap 23 between them, and they are axially aligned with each other.

FIG. 2 is an exploded view from the side showing the components of a timer constructed according to the invention. The specific construction of the above-defined components of the invention is more clearly illustrated in FIG. 2. Generally, each of the wheels 14 and 22 is of known construction comprising a cylindrical circumferential surface area 27 which often has numerals from 0 to 9 printed thereon, although such numerals are not necessary in this instance. Each wheel also comprises a cam surface 28, offset from the surface 27 shown only on wheel 14, and an integral geared portion 29, shown only on wheel 22. The orientation of these wheels must be such that the cam surface 28 of the wheel 14 faces the geared portion 29 of the other wheel 22.

The cam surface 28 comprises a recess 31, into which the teeth of the pinion 26 mesh, thereby causing the pinion to rotate as the wheel 14 turns. To this end, the pinion is provided with two sets of teeth 32 and 34. The two sets have the same root diameter and the same crown diameter but have different axial lengths. The first set of teeth, of which only the teeth 32a and 32b are visible, has the greater axial length, generally as long as the cylindrical portion 33 of the pinion. The second set, of which only the teeth 34a-34c are visible, is only half as long as the first. It will be seen that a tooth from the first set is capable of engaging both of the wheels 14 and 22 simultaneously, while a tooth from the second set is capable of engaging only the wheel 22, at its geared portion 29.

In operation then, the motor 10 causes the wheel 14 to rotate continuously at any desired speed. Two teeth 32a and 32b, for example, of the pinion 26 will be in contact with, and riding along the cam surface 28 until the recess 31 approaches. Tooth 34a will be in engagement with the gears 29 of wheel 22. As the rotation of the wheel 14 continues, the recess 31 will move to fit over the tooth 32a rotating the pinion 26 to a position wherein the tooth 34b will be in engagement with the gears 29 of wheel 22 and the teeth 32b and 32c will be in a position to ride along the cam surface 28. This rotation of the pinion is transmitted directly to the wheel 22,

since the teeth 34a and 32a engage the geared portion 29 of the wheel 22. The arrangement is such that the wheel 22 will make one full revolution for every 10 revolutions of the wheel 14.

As described above, the wheel 22 is fixed to the shaft 17. Therefore, when the wheel moves, it rotates the shaft also. Mounted behind the frame piece 18, relative to the wheel, and on the shaft 17 is a pair of discs 36 and 37. The edges 38 and 39, respectively, comprise nonuniform cam surfaces, and a pair of cam followers 41 and 42 with their respective contact points 43 and 44 are arranged to ride along and follow the contours of the cams. It should be noted that there may be more than one pair of discs and more than one pair of cam followers. The discs 36 and 37 are releasably fixed to the shaft 17 so that they may be adjusted as desired. Upon proper adjustment, they may be fixed so that they rotate when the shaft rotates. The contours in the edges 38 and 39, such as jogs 46 and 47, respectively, have the effect of either separating contact points 43 and 44 or closing them, as desired. The jogs are preferably sharp drops so that the opening or closing of the contact points will be fast and efficient and, because the wheel 22 and the shaft 17 rotate at the same instantaneous angular velocity as the wheel 14 during those intermittent periods of motion of the wheel 22, the exact timing of actuation of the cam followers 41 and 42 may be very accurately controlled. This timing of actuation may even be indicated by setting the edges 38 and 39 to predetermined angular positions indicated by the numerals on the surfaces of the wheels 14 and 22.

What is claimed is:

1. A timer comprising:
a first shaft;
a motor to rotate said shaft;
a first counter wheel on said shaft;
a geneva pinion to be selectively engaged by said first

counter wheel;
a second counter wheel to mesh with said geneva pinion to be moved thereby in defined intervals, said first counter wheel comprising a cam surface to engage the teeth of said geneva pinion, said cam surface comprising a recess to fit over one of said teeth once each revolution of said first counter wheel, thereby to drive said geneva pinion in short intervals of motion.

2. The timer of claim 1 wherein said geneva pinion comprises:

a first set of teeth;
a second set of teeth, said second set being arranged to engage only one of said first and second counter wheels.

3. The timer of claim 1 wherein said first and second counter wheels are of the same diameter so that said second counter wheel will rotate at the same instantaneous speed as said first counter wheel during the time said first wheel drives said pinion.

4. The timer of claim 1 wherein said first and second counter wheels are axially aligned and juxtaposed with each other, said pinion being arranged therebetween and in engagement therewith.

5. The timer of claim 1 comprising in addition: a second shaft, said second counter wheel being mounted thereon.

6. The timer of claim 5 in which said rotatable cam surface is fixed to said second shaft, to be turned thereby when said second counter wheel is driven by said geneva pinion.

7. The timer of claim 1 comprising in addition: at least one electrical contact to be actuated by said second counter wheel.

8. The timer of claim 7 in which said electrical contact is actuated by a rotatable cam surface.
